US00D817745S

(12) **United States Design Patent** (10) **Patent No.:** **US D817,745 S**
(45) **Date of Patent:** **** May 15, 2018**

(54) **HOOK**

(71) Applicant: **3M INNOVATIVE PROPERTIES COMPANY**, St. Paul, MN (US)

(72) Inventors: **Bryan Berger**, Minneapolis, MN (US); **Angela L. Pan**, Arden Hills, MN (US)

(73) Assignee: **3M INNOVATIVE PROPERTIES COMPANY**, St. Paul, MN (US)

(**) Term: **15 Years**

(21) Appl. No.: **29/594,044**

(22) Filed: **Feb. 15, 2017**

(51) LOC (11) Cl. **08-05**

(52) U.S. Cl. **USPC D8/367**

(58) **Field of Classification Search**

(57) **CLAIM**

The ornamental design for a hook, as shown and described.

DESCRIPTION

FIG. 1 is a perspective view of a first embodiment of a hook showing the new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of a second embodiment of a hook showing the new design;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

In the drawings, the dash-dot-dash lines represent boundaries of the claim. The portions of the hook in FIGS. 1-14 shown in broken lines are included to show features that form no part of the claimed design.

1 Claim, 11 Drawing Sheets
